UNITED STATES PATENT OFFICE.

THOMAS WILLIAM CAREY, JR., OF NEW ORLEANS, LOUISIANA.

FLYING-MACHINE.

1,035,687.

Specification of Letters Patent. Patented Aug. 13, 1912.

Application filed May 2, 1911. Serial No. 624,537.

To all whom it may concern:

Be it known that I, THOMAS W. CAREY, Jr., a citizen of the United States, and a resident of New Orleans, in the parish of 5 Orleans and State of Louisiana, have invented a new and Improved Flying-Machine, of which the following is a full, clear, and exact description.

This invention relates to a new and improved flying machine, and particularly to 10 the means for controlling the equilibrium and balance of the same.

It has been found in aeroplanes, that in circling to make a turn, the aeroplane as a 15 whole tilts sidewise, due to the centrifugal force and resistance. If too short a turn is tried, this tilting or inverse angle of inclination becomes, at least dangerous, if not disastrous, as there is a tendency for the 20 flying machine to fall with its side edge downward, offering little or no resisting surface to the air.

It is therefore an object of this invention to provide a flying machine with one or 25 more sets of equilibrium planes and ailerons adapted to counteract this tilting action and reduce the inverse angle, whereby shorter turns may be accomplished with less danger.

A further object of this invention is to 30 provide a flying machine with one or more sets of equilibrium planes adapted to be tilted to form a dihedral angle, and co-operatively connected with ailerons adapted to turn in opposite directions simultaneously 35 with the manipulation of the equilibrium planes, whereby the equilibrium and tilting of the flying machine can be controlled to a nicety.

These and further objects, together with 40 the construction and combination of parts, will be more fully described hereinafter and particularly set forth in the claims.

Reference is to be had to the accompanying drawings forming a part of this specification, in which similar characters of reference indicate corresponding parts in all the views, and in which—

Figure 1 is a fragmentary top plan view; 50 Figs. 2 and 3 are fragmentary perspective views of the left and right-hand portions of the aeroplane, showing the equilibrium planes and ailerons tilted into one of their positions, as for example, in making a turn to the right, whereby they will counteract to 55 a certain extent the tendency of the aeroplane to tilt to the right; Fig. 4 is a frag-

mentary sectional view showing the means for operating one of the equilibrium planes; Fig. 5 is a section taken at right-angles to that in Fig. 4, and showing the same detail; Fig. 6 is a longitudinal section on the line 6—6 of Fig. 1; and Fig. 7 is a detail showing the connection of the controlling ropes to the controlling wheel.

Referring more particularly to the separate parts of this invention as embodied in the form shown in the drawings, 1 indicates an aeroplane, which may be of any suitable type, such as a monoplane, biplane, or the like, and in this instance is shown in the form of a monoplane having a single supporting plane 2 secured in any well known manner to a frame 3. In order to take the strain off the extreme ends of the supporting plane 2, due to the flying machine forcing its way through the air, there is provided a truss arrangement, indicated at 4, which is shown in the form of a tie 5 secured at its ends to the outer ends of the supporting plane 2, and passing over, in intermediate its ends, struts 6 and 7 projecting forwardly in the longitudinal direction of the flying machine, whereby the strain on the ends of the supporting plane is transmitted to points adjacent the frame 3. It 85 will be seen that this truss arrangement extends substantially in the plane of the supporting plane 2, and projects forwardly from the front edge thereof.

At each side of the supporting plane 2, and in fact at times forming extensions thereof, there is provided a movable plane, which, for the sake of distinction, will be called an equilibrium plane. These equilibrium planes are indicated at 8 and 9. 90 The equilibrium planes 8 and 9 are pivoted intermediate their side edges in any well known manner, as by means of longitudinally-extending axes 10. In addition to the equilibrium planes 8 and 9, there are provided ailerons 11 and 12, in this instance shown as pivotally mounted in cut-out portions of the supporting plane 2 and located adjacent the rear edge of the supporting plane 2 at each side thereof. These ailerons are shown in the form of planes pivotally supported intermediate their front and rear edges in any suitable manner, as by means of axes 13. While the equilibrium planes and the ailerons may be operated separately, 105 it is preferable that they be operated in unison, so as to combine their effect in control-

ling the position and equilibrium of the flying machine. Any suitable means for effecting this control may be utilized, and in this instance, I have shown a controlling member 14, in the form of a hand-wheel having a shaft 15 secured thereto. This shaft 15 is rotatably mounted in any suitable manner on the frame 3, and is provided with a drum 16, over separate portions of which extend 10 flexible connections 17 and 18. These flexible connections may be fixedly secured to the drum 16, so as to prevent slipping, or may depend on a plurality of turns to transmit the driving movement of the hand-wheel 14 15 to the drum 16. One end of each of the flexible connections 17 and 18 extends over suitable guide pulleys, indicated at 19, to the under side of the ailerons 11 and 12, respectively, beyond their pivotal axes, where 20 they are secured adjacent the rear edges of the ailerons and pass up over ailerons and in the opposite direction, to points where they are secured to equilibrium-plane operators 20, which in this instance are shown in the 25 form of bell crank lever pulleys rotatably mounted on brackets 21. In passing to and from the point of connection with the rear edges of the ailerons, the flexible connections pass over the ends of levers 120, which 30 project on opposite sides of the ailerons to form attaching points. The opposite ends of the flexible connections 17 and 18, after passing over suitable guide pulleys 22, are also connected to the operators 20, but extending thereto in the opposite direction. 35 The two ends of the flexible connections 17 and 18 may pass through an opening 23 in the operators, so as to secure the same fixedly to the operators, thereby preventing any 40 slipping. The operators 20 may be connected in any suitable manner to the equilibrium planes 8 and 9, as for example, by the connection 24, which is shown to be a universal connection, so as to permit of the relative 45 pivotal movement of the operators and the equilibrium planes. In this instance, the connecting member 24 is shown as comprising a bracket 25 secured to the equilibrium plane, a link 26 pivotally secured to the 50 bracket 25, so as to swing in one direction, and a bracket 27 pivotally connected to the link 26, so as to swing at right angles to the swinging movement of the link 26 relative to the bracket 25. The bracket 27 may be adjustably secured to the operator 20 in any suitable manner, as by means of a slot-and-bolt connection 28. It will be noted that 55 when the equilibrium planes 8 and 10 are in their horizontal position corresponding to the plane of the supporting plane 2, and practically forming a continuation thereof, the operators and the connecting mechanism between the operators and the equilibrium planes, will be in the position shown in 60 Figs. 4 and 5, that is, with the bolt 28 sub-

stantially in alignment with the pivotal axes of the operators 20, with the elements of the connecting member 24 substantially in alignment, representing a dead-center position, whereby a rotation of the operators in either direction will of necessity force the inner and shorter end of each of the equilibrium planes 8 and 9 downwardly, thereby forcing the outer and longer portions of the equilibrium planes 8 and 9 upwardly, thus 70 forming a dihedral angle. It will be further seen that the movement of the equilibrium planes 8 and 9 is simultaneous with the movement of the ailerons 11 and 12, and that this movement will always be from a 75 horizontal position upward, to form a dihedral angle irrespective of whether the major portion of the aileron 11 is turned up or down.

The flying machine may be given its propelling force by any suitable type of propeller, such as that indicated at 29, driven by any suitable type of motor, such as an 80 explosion engine, indicated at 30.

The operation of the device will be readily understood when taken in connection with the above description. During a straight-away flight, the equilibrium planes 8 and 9 are maintained in a normal horizontal position, in alignment with the supporting plane 2 forming an extension thereof. This is also true of the ailerons 11 and 12. When it is desired to make a turn, say for example, to the right, this is done by manipulating a vertical steering rudder (not 90 shown) by any suitable means, and simultaneously turning the wheel 14, so as to pull on the under run of the flexible connection 18 and the upper run of the flexible connection 17, thereby simultaneously tilting the forward end of the aileron 12 upwardly, and the forward end of the aileron 11 downwardly. This action, it will be readily understood, will tend to raise the right-hand side of the aeroplane, and depress the left-hand side (facing to the front), thereby tending to counteract the normal tilt due to 95 centrifugal force and resistance in making the turn. This effect is also aided by the simultaneous movement of the equilibrium planes 8 and 9, which will be swung with their outer ends up, as indicated in Figs. 2 and 3, thereby forming an inverse dihedral angle. The right equilibrium plane 9 will thereby offer a substantially flat surface, 100 forming a supporting surface for the right side of the aeroplane, which in this instance will be the lower. The upper surface of the left equilibrium plane 8 will catch the air 105 passing over the edge of the right equilibrium plane 9, and thereby act to tend to return the flying machine to a normal level 110 keel. It will be found that this action will 115 reduce the cant or tilt of the flying machine 120 in making a short turn, to a considerable 125 amount. 130

extent, so that shorter turns can be made with less danger. It is to be understood that a turn to the left would be accomplished in a similar manner, the aileron 11 assuming 5 a forward and upward inclination, and the aileron 12 a forward and downward inclination, while the equilibrium planes 8 and 9 will again be tilted with their outer ends up, so as to form an inverse dihedral angle, 10 as above, the major portions of the equilibrium planes extending above the supporting plane 2.

While I have shown one embodiment of my invention, I do not wish to be limited to 15 the specific details thereof, but desire to be protected in various changes, alterations and modifications which may come within the scope of the appended claims. It is to be understood that the arrangement can be 20 readily adapted to any type of aeroplane, whether it has one or more supporting planes, and if a plurality of supporting planes are used, the equilibrium planes and ailerons may also be multiplied and connected to move in unison.

Having thus described my invention, I claim as new and desire to secure by Letters Patent:—

1. The combination with a frame, of one 30 or more supporting planes on said frame, an equilibrium plane and an aileron pivotally mounted adjacent one another in each side of the supporting plane so as to normally extend in the same plane with the latter, 35 and having their axes at right-angles to one another, and means to simultaneously actuate the said equilibrium planes and ailerons at opposite sides, in relatively opposite directions whereby the former may be moved 40 to slope toward one another at an inverted dihedral angle.

2. The combination with a frame, of one 45 or more supporting planes on said frame, a pair of pivotally-mounted equilibrium planes, manually-controlled mechanism for moving said equilibrium planes from a normal horizontal position to positions wherein the equilibrium planes slope toward each other at an inverted dihedral angle, and a 50 pair of pivotally-mounted ailerons operatively connected so as to move simultaneously in opposite directions at the same time that said equilibrium planes move.

3. The combination with a frame, of one 55 or more supporting planes on said frame, a pair of equilibrium planes pivotally mounted at a point a greater distance from their outer side edges than from their inner side edges, and mechanism for simultaneously 60 moving the inner edges of both the equilibrium planes downwardly and simultaneously moving both of the outer edges upwardly.

4. The combination with a frame, of one

or more supporting planes on said frame, a 65 pair of equilibrium planes pivotally mounted at a point a greater distance from their outer side edges than from their inner side edges, mechanism for simultaneously moving the inner edges of both the equilibrium 70 planes downwardly and simultaneously moving both of the outer edges upwardly, a pair of pivotally-mounted ailerons, and connections between said ailerons and said mechanism adapted to simultaneously tilt 75 said ailerons in opposite directions with the movement of said equilibrium planes.

5. The combination with a frame, of one 80 or more supporting planes on said frame, a pair of equilibrium planes pivotally mounted so as to swing about longitudinal axes, a pair of ailerons pivotally mounted so as to swing about transverse axes, and mechanism for simultaneously tilting the major portion 85 of said equilibrium planes upward and inclining said ailerons in opposite directions.

6. The combination with a frame, of one 90 or more supporting planes on said frame, a pair of pivotally-mounted equilibrium planes, an operator for each of said equilibrium planes, a pair of pivotally-mounted ailerons, a hand wheel, and operative connections between said hand-wheel and said ailerons and between said hand-wheel and 95 said operators.

7. The combination with a frame, of one 100 or more supporting planes on said frame, a pair of pivotally-mounted equilibrium planes, a rotatably-mounted pulley for each of said equilibrium planes, a link connection between each of said equilibrium planes and each of said pulleys, a hand wheel, and flexible connections between said hand-wheel and said pulleys.

8. The combination with a frame, of one 105 or more supporting planes on said frame, a pair of pivotally-mounted equilibrium planes, a rotatably-mounted pulley for each of said equilibrium planes, a link connection between each of said equilibrium planes and each of said pulleys, a hand wheel, flexible connections between said hand-wheel and said pulleys, and a pair of pivotally-mounted ailerons, said flexible connections being so connected to said ailerons as to simultaneously manipulate them in opposite directions at the same time that said equilibrium planes are manipulated by said pulleys.

9. The combination with a frame, of one 120 or more supporting planes on said frame, a pair of movably-mounted equilibrium planes, a pair of movably-mounted ailerons, means for simultaneously manipulating said ailerons so as to incline in opposite directions, and an operator manipulated by said 125 means, for turning said equilibrium planes always in the same direction, irrespective of the movement of said ailerons.

10. The combination with a frame, of one or more supporting planes on said frame, a pair of pivotally-mounted equilibrium planes, a rotatably-mounted operator for manipulating each of said equilibrium planes, a universal connection between each of said operators and each of said equilibrium planes for allowing for the relative pivotal movement of said operators and said equilibrium planes, and means for manipulating said operators.

11. The combination with a frame, of one or more supporting planes on said frame, a pair of pivotally-mounted equilibrium planes, a pair of pivotally-mounted ailerons, a pulley-operator for each of said equilibrium planes, a link connection between each of said pulleys and said equilibrium planes, a hand-wheel, and a flexible connection operated by said hand-wheel, connected to each of said ailerons and passing over each of said pulleys, whereby said equilibrium

planes and said ailerons may be simultaneously manipulated.

12. The combination with a frame, of one or more supporting planes on said frame, a pair of pivotally-mounted equilibrium planes, a pair of pivotally-mounted ailerons, a pulley-operator for each of said equilibrium planes, an adjustable link connection between each of said pulleys and said equilibrium planes, a hand-wheel, and a flexible connection operated by said hand-wheel, connected to each of said ailerons and passing over each of said pulleys, whereby said equilibrium planes and said ailerons may be simultaneously manipulated.

In testimony whereof I have signed my name to this specification in the presence of two subscribing witnesses.
